United States Patent Office.

N. A. VURGASON, OF BROOKLYN, NEW YORK.

Letters Patent No. 82,772, dated October 6, 1868.

IMPROVEMENT IN SKIRT-SUPPORTERS.

The Schedule referred to in these Letters Patent and making part of the same.

TO ALL WHOM IT MAY CONCERN:

Be it known that I, N. A. VURGASON, of Brooklyn, in the county of Kings, and State of New York, have invented a new and improved Skirt-Supporter; and I do hereby declare that the following is a full, clear, and exact description thereof, which will enable others skilled in the art to make and use the same, reference being had to the accompanying drawings, forming part of this specification.

Figure 1 is a perspective view of my invention.

Figure 2 is a sectional view of the spring-catch.

Similar letters of reference indicate corresponding parts.

The nature of this invention relates to the supporting of ladies' skirts, whereby the weight of the latter is not required to be sustained by tying the same tightly around the waist with strings or similar fastenings.

It is conceded by all medical authorities the general health of females is greatly impaired by the pernicious practice of wearing a number of under-skirts to give the desired contour to the skirt of the exterior dress. The principal objection to this practice lies in the compression or strangulation of waist of the wearer by the string-fastening necessary to support the skirts, as the mere weight of the latter would not be, if properly supported, so prominently objectionable.

My invention is designed to support such skirts in a manner which will enable ladies to indulge in the wearing of the maximum number with the minimum injurious effect.

It consists of a band or zone formed of sheet metal, stiff leather, pasteboard, horn, hard rubber, gutta-percha, or any other suitable material.

The said zone is divided into two equal halves, and hinged together to enable the same to be opened in the act of putting it off or on, or adjust the same to fit the wearer.

The meeting-ends of the two parts of the zone are provided with any suitable spring-catch and correspondent holes, for holding the zone firmly when in use, and adjusting the same to the wearer, as aforesaid.

A number of hooks is affixed around the exterior of the zone for the purpose of attaching thereto the skirts to be worn, the said skirts being provided with suitable loops or eyelets at intervals, corresponding to the said hooks.

A fillet of soft leather, kid-skin, or other suitable material, is sewed or otherwise affixed to the upper edge of the zone, which is flanged outwardly and perforated for that object.

The inner surface of the zone is made convex, so as to conform more nearly to the hips and waist, and is covered with any suitable soft material, as buckskin or cloth, to prevent it from feeling harsh to the wearer.

Hoop-skirts or crinoline may also be attached to this zone, and the weight of any or all of such skirts will be sustained upon the hips, and not by means of strings drawn tightly around the waist.

The invention has also the additional advantage of enabling the skirts to be put off or on with little trouble, and in a few seconds.

In the accompanying plate of drawings, the zone is shown at A A, having the hooks a a, &c., and hinge b.

B is the fillet of soft leather, covering the hooks, and protecting the outer garments from being grazed thereon.

C is the inner surface-covering, of buckskin.

c c c, &c., are the holes for receiving the point d of the spring-catch D, as shown more in detail at fig. 2.

E is a hoop-skirt, attached to the hooks by loops.

The hooks are made large enough to receive the several loops of different skirts.

G is a margin, of morocco leather or other similar material, which is stitched to the lower edge of the zone, to complete the zone with a suitable finish.

I claim as new, and desire to secure by Letters Patent—

The skirt-supporter, constructed, as described, of the hinged metallic zone A A, whose ends are secured together by the overlapping spring-catch D, and whose outer surface is provided with the hooks a a, covered and protected by the flap or fillet B, said zone being attached at its lower edge to the inner curtain or flap G, all arranged as described, for the purpose specified.

N. A. VURGASON.
